UNITED STATES PATENT OFFICE

2,678,683

CHAIR AND DESK CONSTRUCTION

William James Bargen, Waukegan, Ill.

Application May 10, 1951, Serial No. 225,565

4 Claims. (Cl. 155—124)

1

This invention relates to a chair and a desk construction.

An object of this invention is to provide a chair and a desk embodying an improved top and seat with an improved supporting frame structure for the chair and desk.

Another object of this invention is to provide an improved frame structure for a chair and a desk, wherein the legs are connected together in pairs beneath the central portion of the seat, and a combined seat supporting and leg bracing tie bar is fixed between each pair of legs. This tie bar also serves as a means for relieving any strain from the seat on the connection between the pairs of legs.

A further object of this invention is to provide an improved frame structure which will resiliently support the top and will also permit the use of a resilient seat structure.

A further object of this invention is to provide an improved desk top which is formed with a pair of rearwardly projecting arms which serve as arm rests for a person disposed in the seat and permit the use of the top for right or left handed persons.

A further object of this invention is to provide a frame structure for a chair and desk which is formed out of tubular material, and includes counterbalancing means to hold the assembly against forward tilting.

A further object of this invention is to provide a frame structure which will withstand rough and hard usage and will not crack or break under sudden shocks or undue strains.

With the above and other objects in view, my invention consists in the arrangement, combination and details of construction disclosed in the drawings and specification, and then more particularly pointed out in the appended claims.

In the drawings:

Figure 1 is a top plan view of a combined chair and desk constructed according to an embodiment of this invention;

Figure 2 is a detail side elevation of the device partly in section;

Figure 3 is a sectional view taken on the line 3—3 of Figure 2;

Figure 4 is a sectional view taken on the line 4—4 of Figure 2;

Figure 5 is a fragmentary sectional view taken on the line 5—5 of Figure 2;

Figure 6 is a perspective view of the frame structure;

Figure 7 is a fragmentary rear elevation of the pencil holder;

2

Figure 8 is a detail side elevation of a chair having a base constructed according to this invention;

Figure 9 is a perspective view of the chair base shown in Figure 8;

Figure 10 is a fragmentary sectional view taken on the line 10—10 of Figure 2;

Figure 11 is a fragmentary sectional view similar to Figure 3 of a modified form of this invention;

Figure 12 is a fragmentary plan view of a modified form of chair base.

Referring to the drawings and first, to Figures 1 to 10, inclusive, the numeral 15 designates generally a frame structure which is formed of a pair of front legs 16 and 17 and a pair of rear legs 18 and 19.

The front legs 16 and 17 are connected together by means of a substantially V-shaped connecting member 20 formed with a truncated rear end 21 and the rear legs 18 and 19 are connected together by means of a V-shaped member 22. The apex or forward end of the V-shaped member 22 is secured to the inner end 21 of V-shaped member 20, as by welding 23, or the like. Preferably, the connection between the two members 20 and 21 is to one side of the transverse median of connecting member 21 so that leg 17 will be offset laterally. A connecting bar 24 is welded or otherwise fixedly secured to the divergent rear ends of the V-shaped member 22 and a second connecting bar 25 is welded or otherwise fixedly secured to the divergent ends of the V-shaped member 20. A pair of right-angularly disposed top supporting bars 26 and 27 are disposed in forwardly and upwardly offset relation to the tie or connecting bar 25 and bar 26 is formed integral with a downwardly and rearwardly extending bar 28 which is integral with a rearwardly projecting and obtusely disposed bar 29. The bar 29 is formed integral with the rear tie bar 24 and is adapted to be disposed along one edge of the seat, as will be hereinafter described.

The bar 27, which is transversely disposed with respect to the top and is substantially longer than the bar 26, is formed integral with a downwardly extending bar 30. The bars 25, 27 and 30 form a U-shaped member and the bars 28 and 30 are adapted to be welded together along the length thereof so as to provide a substantially rigid and slightly resilient support for the top 31.

The top 31, as shown in Fig. 2, is provided with a pair of rearwardly projecting arms 32 and 33 with the arm 32 substantially longer than the arm 33 and arm 32 narrower than arm 33. These

55

arms 32 and 33 provide rests for the arms of the person disposed in the seat and also accommodate left and right hand persons to their respective posture habits. The top 31 is secured to the supporting arms 26 and 27 by means of screws 34 or other suitable fastening means. The rear legs 18 and 19 are weighted so as to provide a counterbalancing means for the frame structure by means of a weight 35 which is disposed within each leg 18 and 19.

A seat structure embodying a seat member 36 is secured on the tie bars 24 and 25 by fastening members 37 and 38 and the bottom of the seat member 36 is slightly spaced from the V-shaped members 26 and 27. The seat member 36 has an upwardly extending back member 39 projecting from the rear thereof and the juncture between the back member 39 and the seat member 36 is formed on a concave curvature, as indicated at 40.

As shown in Figure 2, the curved connecting member 40, between the seat and the back, projects rearwardly from the rear tie bar 24, so that the back 39 may be bent rearwardly under strain of the person in the seat. The top 31 has secured to the lower side thereof on one end a pencil or pen holder 41. The holder 41 includes a base 42 which is secured by fastening means 43 to the lower side of the top 31. A downwardly extending wall 44 projects from the base 42 and a slotted bottom wall 45 extends horizontally from the inner depending wall 44 and terminates in an upwardly curved outer portion 46. A pair of end walls 47 depends from the opposite ends of the base 42.

Referring to Fig. 10, it will be noted that each leg has secured to the lower end thereof a glider 48 which is carried by a cup-shaped mounting 49 and a rubber cushion member 50 is interposed between the mounting 49 and the glider 48.

Referring now to Fig. 11, there is disclosed a modified form of this invention, wherein the front legs 16a and 17a have projecting rearwardly from the upper ends thereof extensions 51 and 52, respectively. The extensions 51 and 52 diverge forwardly and a tie bar 53 is secured between the outer end portions of the extensions 51 and 52. Preferably, extension 52 is formed with an inwardly offset inner portion 54, so that the leg 17a will be offset laterally a greater distance than leg 16a.

A crossed tubular connecting member 55 is telescoped over and secured to the inner ends of extension 51 and offset extension 54 and is also telescoped over and secured to the inner ends of extensions 56 and 57 which project from legs 18a and 19a. The extensions 56 and 57 are connected together by means of a tie bar 58.

The frame structure 15 is preferably formed of tubular material so as to provide a relatively rigid and light weight frame structure, wherein the desk forming top 31 will be substantially resiliently supported with respect to the chair. The two secured together members 28 and 30 provide an upwardly and forwardly projecting supporting arm for the top which is integral with the front and rear tie bars 25 and 24, respectively.

In Figures 8 and 9 there is disclosed a chair and chair base structure wherein the seat 58 and back 59 are similar to the seat 36 and back 39. A base generally designated as 60 is secured beneath the seat 58 and comprises a pair of front legs 61 and a pair of rear legs 62. A V-shaped member 63 extends rearwardly from legs 61 and a second oppositely disposed V-shaped member 64 extends forwardly from legs 62. The apices of the V-shaped members 63 and 64 are fixed together as by welding 65 or other suitable fastening means. A front tie bar 66 is secured between the forward or divergent ends of the V-shaped member 63, and a rear tie bar 67 is secured between the divergent ends of rear of V-shaped member 64.

5

61 and a second oppositely disposed V-shaped member 64 extends forwardly from legs 62. The apices of the V-shaped members 63 and 64 are fixed together as by welding 65 or other suitable fastening means. A front tie bar 66 is secured between the forward or divergent ends of the V-shaped member 63, and a rear tie bar 67 is secured between the divergent ends of rear of V-shaped member 64.

10

In Figure 12 there is shown a modified form of chair base using the construction shown in Figure 11 wherein the legs have inwardly convergent bars 68 and 69 extending from the front and rear, and bars 68 and 69 are fixed in a crossed connector 70 similar to connector 55. The bars 68 are connected together at their outer divergent ends by means of a tie bar 71, and a similar tie bar (not shown) is secured between the rear divergent ends of bars 69.

20

It will be apparent that the combined seat and back structure may be used interchangeably with the several chair base frames, and that these chair base frames may be used in the formation of a desk frame structure as herein disclosed.

25

In the chair base structures shown in Figures 8, 9, and 12 the weights shown in Figure 2 are preferably omitted.

From the foregoing description and the accompanying illustrations it will be noted that some of the functional features which are accomplished are as follows:

Left handers and right handers can use the same top.

Workers are balanced in posture with equal muscular tension right and left.

Workers can use the back to better advantage with two arms permitting correct posture.

Two arms tend to keep workers in balanced position eliminating fatiguing body twist.

Two arms enlarge the practical working surface of the top.

Two arms "lean the body back" so as to encourage proper relationship of the eyes to the working surface.

Two arms give a resting point for the elbows when reading books or papers at about 45 degrees.

Two arms "lean the body back" so as to take the strain off the feet and the calves and the knees and so as to cause the body to rest properly within the back resulting in absence of fatigue and causing relaxation.

The arms reduce vibration and strain within the desk because the worker in his "balanced position" tends to move less within the structure in his search for working relaxation.

What is claimed is:

1. A chair and desk frame, comprising a chair base formed of front and rear legs, a pair of oppositely disposed V-shaped members one extending from one of said front legs to the other and the other extending from one of said rear legs to the other, means securing the apices of said members together, a pair of tie bars fixed one each to the outer divergent ends of said V-shaped members, a pair of right-angularly related top supporting bars, and means supporting said top supporting bars in offset relation with respect to said base, said latter-named means being formed integral with said tie bars.

2. A chair and desk frame, comprising a chair base formed of front and rear legs, weight means within said rear legs, a pair of oppositely disposed V-shaped members one extending from

one of said front legs to the other and the other extending from one of said rear legs to the other, means securing the apices of said members together, a pair of tie bars fixed one each to the outer divergent ends of said V-shaped members, a pair of right-angularly related top supporting bars, and means supporting said top supporting bars in offset relation with respect to said base.

3. A chair and desk frame, comprising a chair base formed of front and rear legs, a pair of oppositely disposed V-shaped members one extending from one of said front legs to the other and the other extending from one of said rear legs to the other, means securing the apices of said members together, a pair of tie bars fixed one each to the outer divergent ends of said V-shaped members, said tie bars being disposed on the upper sides of said V-shaped members, a pair of right-angularly related top supporting bars, and means supporting said top supporting bars in offset relation with respect to said base.

4. A chair frame construction comprising a

base formed of a pair of front legs, a pair of rear legs, a pair of oppositely disposed substantially V-shaped members one extending from one of said front legs to the other, the other one of said members extending from one of said rear legs to the other, means securing said members together at their apices, and a pair of tie bars fixed one each to the outer divergent ends of said V-shaped members, said legs all being of tubular construction and said front legs being spaced apart from each other a greater distance than the spacing of said rear legs from each other.
